PNEUMATIC TIRE TREAD AND BUTTRESS

Carl F. Smajd, St. Clair Shores, Mich., assignor to
Uniroyal, Inc., New York, N.Y.

Filed May 18, 1973, Ser. No. 362,040

Term of patent 14 years

Int. Cl. D12—15
U.S. Cl. D12—147

Fig. 1.

71 9 2.

FIG. 1 is a perspective view, partly schematic for a pneumatic tire tread and buttress embodying my new design, it being understood that the pattern is repeated throughout the circumference of the tread and buttress, as shown schematically by solid lines, and that the buttress pattern is repeated on the opposite side;

FIG. 2 is an enlarged, fragmentary development plan view of the tread and buttress of FIG. 1;

FIG. 3 is an enlarged, sectional view of the tread and buttress, taken substantially as indicated by line 3-3 of FIG. 2;

FIG. 4 is an enlarged, fragmentary sectional view of the buttress, taken substantially as indicated by line 4-4 of FIG. 2; and

FIG. 5 is an enlarged, fragmentary sectional view of the buttress, taken substantially as indicated by line 5-5 of FIG. 2.

I claim:

The ornamental design for a pneumatic tire tread and buttress, substantially as shown and described.
